UNITED STATES PATENT OFFICE.

GEORGE ALBERT NELSON, OF LINDSBORG, KANSAS.

TERMINAL PULLER.

Application filed December 17, 1923. Serial No. 681,252.

To all whom it may concern:

Be it known that I, GEORGE A. NELSON, a citizen of the United States, residing at Lindsborg, in the county of McPherson and State of Kansas, have invented certain new and useful Improvements in Terminal Pullers; and I do declare the following to be a full, clear, and exact description of the invention, such as will enable others skilled in the art to which it appertains to make and use the same.

My invention has for its object to provide a simple and inexpensive, yet a desirable and efficient device for pulling off the terminals from storage batteries.

With the foregoing in view, the invention resides in the novel subject matter herein-after described and claimed, the description being supplemented by the accompanying drawing.

Figure 1 is a side elevation showing the application of my invention in removing a battery terminal.

Figure 2 is an enlarged vertical sectional view partly in elevation.

Figures 3 and 4 are horizontal sectional views on lines 3—3 and 4—4 of Fig. 2.

In the preferred form of construction, selected for illustration in the present application, the numeral 1 designates a cross head having a central opening 2 and bifurcated ends 3. Pivotally mounted in these bifurcated ends, on rivets or other suitable pivot pins 4, are two elongated levers 5, the pivots 4 being adjacent the lower ends of said levers, which ends are curved inwardly toward each other and thinned to provide a pair of jaws 6 for reception under a battery terminal.

Above the pivots 4, the levers 5 diverge with respect to each other and between them, a screw 7 is disposed, said screw having its lower end threaded through the opening 2 while its upper end is provided with a suitable head or the like 8, by means of which it may be rotated, through the instrumen-

tality of a wrench or similar tool. The lower end of the screw 7 is adapted to thrust against the post surrounded by the battery terminal being removed, so that when said screw is rotated, the head 1 and the levers 5 will be pulled upwardly, thereby causing the jaws 6 to pull the terminal from the post. To prevent inward swinging of the upper ends of the levers 5 during this pulling operation and to consequently prevent release of the jaws 6 from the terminal, I provide a lever spreader 9 which is freely slideable along the screw 7 to abut the levers as shown in Fig. 1. In the preferred construction, this spreader 9 is in the form of a disk having a hub 10 slideable upon the screw 7.

By providing the construction shown and described, or a substantial equivalent thereof, a device is produced which is simple and inexpensive, and may be easily and advantageously used in removing battery terminals or performing similar work.

As excellent results are obtainable from the details disclosed, they are preferably followed, but within the scope of the invention as claimed, numerous minor changes may be made.

I claim:

A device of the class described comprising a cross head having a central transverse opening, a pair of elongated levers fulcrumed near one end to the ends of said cross head and having jaws on said one end, the other ends of said levers being in diverging relation with each other, a screw between said diverging lever ends threaded through said central opening, and a lever spreader slideable freely along said screw for contact with said diverging lever ends to prevent inward movement thereof and consequent release of said jaws.

In testimony whereof I have hereunto affixed my signature.

GEORGE ALBERT NELSON.
